BAG SEALING

William R. Kohl, Glenview, Ill.

Application December 8, 1937, Serial No. 178,645

4 Claims. (Cl. 206—7)

My invention is a bag, and method of sealing a bag.

Other objects are sealing a moth-proof bag; a weather-proof bag; and a self-sealing pressure seal bag capable of repeated opening and repeated sealing.

Further, my invention has a peculiar and inventive application to bags made of transparent material which may be sealed by heat and pressure, and pressure self-sealing, protecting garments against atmospheric conditions, and forms of life having a tendency to injure and destroy garments therein.

The accompanying drawing is an embodiment of my invention, in which

Fig. 1 is a broken section of a bag showing the treatment of the upper portion, the side, and the bottom.

Fig. 2 is a flat view of one primary sealing member.

Fig. 3 is a flat view of a locking member of a seal.

Fig. 4 is a view of an aperture to be sealed after a hanger is inserted thru for support.

Fig. 5 is a broken section of the bottom of a bag, showing the structure of the sealing members.

Fig. 6 is a broken section of the bottom of a bag, showing the device in Fig. 5 closed.

Fig. 7 is a broken section of a modification, in which there is a sealing means inside a bag to strengthen the outside sealing means.

As illustrated I show primarily the device as applicable to a bag preferably made of transparent material which is responsive to sealing under heat and pressure, such as some forms of rubber derivative, or viscose. The same treatment is applicable to bags using a thermoplastic adhesive for union.

The bag 10 is made from a flat sheet folded, with a longitudinal seam 11 by pressing upon the same a heated tool having a serrated form 12, joining the lapping edges of the beam 11; these serrations making long strong lines of union perfectly air tight and stronger than the basic material itself. This tube 10 is flattened and at one end is lapped over on the body at either side 13 and 14 from a central opening 15; the edges 16 and 17 of the lapped portions sealed to the body by heat and pressure in serrated form 12. The opening 15 is provided for the free passage therethru of a hanger for supporting a garment therein. I provide a means for sealing the opening 15 comprising two members, one preferably a double diamond shape 18, Fig. 2, the diamonds

joined at one edge 19 of each adapted to be folded at their junction; the other a single diamond shape 21, to correspond to one portion of 18. These members 18 and 21 are formed out of a substantially tough fabric coated on one side with a substantially non-drying self-sealing adhesive, the adhesive being initially temporarily protected by a fabric 20 easily removed. In the member 18 a scoring of the temporary fabric at 22 is made so that a portion 23 may be removed leaving the arrowhead portion 24 intact, upon which the member 18 is straddled over an inclined edge of the top of the bag, simply pressed against the area adjacent the central opening 15, with the arrowhead portion lines 22 registering 16 with the line 15 of the opening thus leaving an unsealed mouth 25 along the inclined edge of the bag opposite to the edge which is sealed by the lapping thereover with the member 18: the said opening 25 being provided for the passage there-thru of the hook portion of a hanger. The member 21 being relieved of fabric a half portion is adhesively attached to that portion of member 18 which is adhesively attached to the back of the bag, as at 26; the other half of 21 hanging 25 free facing the aperture 25. This completes the bag at its upper portion ready for use. When a garment with a hanger has been placed in the bag and the hook of the hanger has been passed thru the aperture 25 the said portion 21 is lapped 30 over the aperture 25 and pressed down, locking it. The adhesive is of such a character that when not exposed to the atmosphere it retains its adhesive characteristics, and the unsealing portion of 21 may be readily lifted to remove the hanger and 35 then placed back.

On the bottom of the bag the front wall 27 is shorter than the rear wall 28: on the face of the front wall 27 I attach a strip 29 of the adhesively coated material, its outer surface being uncoated; 40 and on the inner face of the rear wall 28, I attach a strip 30 adhesively coated on both sides, the exposed side faced with a temporary fabric 20 to be stripped off after a garment is suspended in the bag and the strip 30 turned up and adhesively attached to the strip 29, thus completing the sealing of the whole bag. A tab 20a is lightly attached to the fabric 20, extends around its edge and is stuck to the back thereof 50 for lifting a beginning end of fabric 20 exposing its coating.

In Fig. 7 I show a modified form in which I place one of the double-diamond shapes 18 inside of the bag in reverse position 18a from the 55

outside form 18, thus giving a double strength to the central opening 15 of the bag.

I do not limit myself to the device as shown and described except in so far as I am limited by the scope of my claims.

I claim:

1. A bag constructed of one piece of material into an elongated flattened tube, one end of said bag having its edges angularly turned over and attached to the body of the bag, the said turned-over edges spaced apart providing a median opening for the passage therethru of a garment-supporting device, a means for sealing said opening consisting of two coactive members each having a coating of non-drying self-sealing adhesive, one of said members being adapted to straddle one of the turned-over edges and be attached at the front and back of the bag immediately adjacent to the median line of the opening and provide a mouth for the passage therethru of the supporting device, the other member adapted to be attached to the straddle member on one side and having a free portion adjacent to be brought over and attached to the opposite straddle member sealing the mouth opening after the supporting member is in position.

2. A bag consisting of a rubber derivative formed into a flat tubular body, its joining seams fused by heat and pressure, one end of said bag having means for being self-sealingly closed when articles have been inserted therein, the opposite end having a restricted opening median thereof, the portions adjacent to either side of the said opening folded upon the body and sealed by fusing to the body of the material, a combination closure of the restricted opening comprising two members, one a double diamond shape and one a single diamond shape, each of the said diamond-shaped portions being constructed of a tough fabric bearing upon one face a non-drying self-sealing adhesive adapted to be sealed by simple sealing pressure thereon, the double portion adapted to straddle one inclined edge adjacent to the median line, one half-portion attachable to the rear and the other half-portion attachable to the front, reinforcing the material at the restricted opening and providing a mouth opening on the inclined side opposite to the straddled member, the single diamond-shaped member being attached by a half portion to one portion of the double diamond-shaped member and having a free portion adjacent to the mouth opening, and adapted, when a hanger hook has been passed thru the same, to be folded over the mouth opening and self-sealed on the other portion of the double diamond-shaped reinforcing member, the single diamond shaped member adapted to be

unsealed on the removal of articles from the bag, and be repeatedly self-sealed by pressure.

3. A garment bag consisting of a flattened tube longitudinally sealed having at one end a restricted opening flanked on either side by laps folded against and sealingly united to the body, the opposite end opening having means to hermetically seal the same, the restricted opening reinforced by a member of a locking combination consisting of two diamond shaped portions adapted to straddle an inclined edge and each be pressure-sealed to the back and front respectively adjacent to the opening and sealingly close said opening to the median line thereof providing a mouth opening along a portion of the opposite inclined edge, said mouth capable of being lockingly sealed by a second member of the locking combination which consists of a member adapted to be self-sealed by pressure to the rear side of the straddle member of the locking combination and having a portion adapted to be closed over the mouth opening of the restricted opening after a hanger hook has been passed thru the same and be self-sealed by pressure on the front side of the reinforcing straddle member of the locking combination.

4. A bag of flattened tubular material sealed longitudinally by heat and pressure, one end having means to be hermetically sealed after the insertion of material therein, the opposite end having a restricted opening thru which to pass the hook portion of a hanger device, and adjacent to the restricted opening on either side thereof of a fold of the bag material, a means to sealingly enclose the restricted opening consisting of two members constituting a locking device, one of said members being a double diamond shape adapted to straddle the inclined edge of one fold, one of said diamond portions respectively attachable to the front and one to the back of the bag to strengthen the restricted opening, and provide a mouth opening on the inclined opposite to the straddled portion, a secondary portion of the locking device consisting of a diamond-shaped member one half of which is attached to a rear portion of the straddled member having a free portion adjacent to the mouth opening adapted to be drawn over and attached to a corresponding face of the double diamond-shaped member and close the opening after the hanger member has passed thru the same, the members of the combined locking device being formed of a fabric primarily bearing upon a surface of each a non-drying self-sealing adhesive adapted to be self-sealed by ordinary pressure and capable of being readily unsealed and being resealed by self-sealing pressure.

WILLIAM R. KOHL.
